UNITED STATES PATENT OFFICE.

JOHN L. GISH, OF JACKSON, MICHIGAN.

RHEOSTAT.

SPECIFICATION forming part of Letters Patent No. 403,345, dated May 14, 1889.

Application filed January 16, 1889. Serial No. 296,512. (No model.)

To all whom it may concern:

Be it known that I, JOHN L. GISH, a citizen of the United States, and a resident of Jackson, in the county of Jackson and State of Michigan, have invented new and useful Improvements in Rheostats, of which the following is a specification.

This invention relates to a rheostat which is provided with a series of resistance-coils and a movable contact-point which bears against one of the coils and to which one end of the instrument-line is connected, so that the contact-point can be adjusted along the coil for the purpose of regulating the shunted current.

15 A rheostat of this description is described and shown in an application for patent filed by me July 12, 1888, Serial No. 279,742. In this rheostat the movable contact-point reaches only a single coil, and when two or more coils are arranged to be partially shunted each coil is provided with a separate contact-point. In such a rheostat the instrument-line has to be shifted from one movable contact-point to another when the adjustment is extended beyond one 25 coil, whereby the shunted current is interrupted and other inconveniences and objectionable results are produced.

The object of my present invention is to construct the rheostat in such manner that a 30 single movable contact-point can be adjusted along two or more coils, thereby increasing the range of adjustment and avoiding any interruption of the shunted current while the adjustment of the contact-point is being made.

35 In the accompanying drawings, Figure 1 is an elevation of a rheostat provided with my improvements. Fig. 2 is a horizontal section thereof. Fig. 3 is a vertical section of the movable contact-point on an enlarged scale. Figs. 4 and 5 are cross-sections in lines xx and yy , Fig. 3, respectively.

Like letters of reference refer to like parts in the several figures.

45 A represents the base, a the top piece, and b the upright board, constituting the frame of the rheostat.

C represents the generator; c , the line running from the generator to the binding-post d of the rheostat at which the current enters the latter; d' , the binding-post at which the current leaves the rheostat, and c' the line

extending from the binding-post d' to the generator.

E E' E² E³ E⁴ E⁵ E⁶ E⁷ represent a series of 55 connected resistance-coils secured to the frame of the rheostat and having the outer ends of the end coils, E E⁷, connected, respectively, with the binding-posts d d' .

As shown in the drawings, the coils E, E', E², and E³ are arranged to be partially shunted out by means of a movable contact-point, F, to which one end of the instrument-line f is connected, while the other end of said line is connected with the binding-post d' . The 60 lower ends of the coils E E' are connected by a flat metallic bar, g , the upper ends of the coils E' E² by a similar bar, g' , and the lower ends of the coils E² E³ by a similar bar, g^2 .

H H' H² H³ represent upright slots or ways 70 formed on the vertical board b of the frame opposite the coils E E' E² E³. The lower ends of the slots H H' are connected by a horizontal slot, h , opposite the bar g , the upper ends of the slots H' H² by a horizontal 75 slot, h' , opposite the bar g' , and the lower ends of the slots H² H³ by a slot, h^2 , opposite the bar g^2 , so that the upright and horizontal slots form a continuous slot or way opposite these coils and their connecting-bars. The movable contact-point F is arranged in this continuous slot or way, so that it can be adjusted 80 in the same along these coils and their connecting-bars without breaking contact in passing from one coil to the other. This contact-point is constructed in the following manner:

I represents a sliding frame arranged in the slot or way of the rheostat-frame and provided on opposite sides of the board b with flanges i i' . The portion of the sliding frame 90 which enters the slot is made square, so as to pass snugly through the vertical and horizontal portions of the slot and support the contact-point in whatever position it is placed.

J represents the binding-post of the movable contact-point, to which the end of the instrument-line f is attached. This binding-post is provided with a socket, j , which enters the outer sleeve portion, i^2 , of the sliding frame I. The socket j carries a projection, j' , 95 which plays in a quadrant-shaped slot, j^2 , in the sleeve i^2 , and limits the rotary movement of the socket j in the sleeve i^2 to a quarter-turn. This projection, engaging in said slot,

also serves to attach the binding-post to the sliding frame I.

K represents a cylindrical bolt arranged in the inner portion of the socket *j*, and *k* is a spring interposed between this bolt and the bottom of the cavity of the socket, so as to press the bolt rearwardly or toward the coil. The bolt is provided at its outer end with an anti-friction roller, *k'*, which runs in contact with the coil.

l is a projection formed on the side of the bolt K and entering a longitudinal groove, *l'*, in the socket *j*, whereby the bolt is compelled to turn with the socket and at the same time is permitted to move lengthwise in the socket in adjusting itself to the coil.

When the movable contact-point is placed at the upper end of the vertical slot H opposite the outgoing end of the coil E, the shunted current is of minimum strength. By moving the contact-point downwardly to the lower end of the coil E, then across to the lower end of the coil E', and then upwardly along the latter coil, the strength of the shunted current is gradually increased, and in this manner the contact-point is moved along and from one coil to another until the desired current is shunted out. This arrangement does away with the interruption of the shunted current in adjusting from one coil to another, and enables a high tension of the shunted current to be reached gradually, which is especially desirable when using a dental lamp, as the carbon loops of such lamps are liable to break when a current of high tension is suddenly applied. It also avoids a multiplicity of movable contact-points, and simplifies the construction of the rheostat. In passing from a coil to a connecting-bar, or vice versa, the socket is given a quarter-turn, thereby placing the anti-friction roller in the proper position to run freely. The anti-friction roller is held by the spring in close contact with the coil or connecting-bar, so as to insure the proper passage of the shunted current. While the anti-friction roller described and shown is preferably used, it is not indispensable, and may be omitted.

I claim as my invention—

1. The combination, with two resistance-coils and their connection, of a movable contact-point and a guide on which the contact-point can be moved along each coil and from one coil to the other along their connection without breaking contact, substantially as set forth. 50

2. The combination, with two resistance-coils and their connection, of a frame provided with a continuous way opposite said coils and their connection, and a movable contact-point arranged in said way and adapted to bear against said coils and their connection, substantially as set forth. 60

3. The combination, with several resistance-coils having their adjacent ends connected by flat metallic bars, of a frame provided opposite said coils and bars with a continuous slot or way, and a movable contact-point arranged in said slot or way, substantially as set forth. 65

4. The combination, with a resistance-coil, of a stationary frame provided with a slot or way opposite said coil, a sliding frame, I, arranged in said slot or way, a binding-post, J, provided with a socket, *j*, arranged in said sliding frame, and a contact-bolt, K, and spring *k*, arranged in said socket, substantially as set forth. 70

5. The combination, with a resistance-coil, of a stationary frame provided with a slot or way opposite said coil, a sliding frame, I, arranged in said slot and provided with a sleeve, *i*, having a slot, *i'*, a binding-post, J, provided with a socket, *j*, arranged in the sleeve *i* and having a projection, *j'*, entering the slot *i'*, a contact-bolt, K, provided with an anti-friction roller, *K'*, and having a projection, *l*, entering a groove, *l'*, in the socket *j*, and a spring, *k*, arranged in said socket behind the contact-bolt, substantially as set forth. 80

Witness my hand this 11th day of January, 1889.

JOHN L. GISH.
